FIG. 3.

UNITED STATES PATENT OFFICE

CHARLES W. GORDON, OF PLEASANTVILLE, NEW YORK, ASSIGNOR TO THE SUPER-HEATER COMPANY, OF NEW YORK, N. Y.

TEMPERATURE-INDICATING MEANS

Application filed February 9, 1929. Serial No. 338,789.

My invention relates to means for indicating temperatures and has particular reference to means for indicating whether or not predetermined temperatures have been exceeded by the heated fluid in a heat exchanging apparatus of the surface or non-contact type, such for example as a steam superheater or an oil heating or cracking still.

In apparatus of this character the heating elements through which the fluid to be heated is passed are frequently located in zones of extremely high temperature produced by combustion gases, and the conditions to which such elements are subjected are so severe that the cooling action of the fluid passing through them must be depended upon to save them from destruction. The fluids heated are, moreover, often raised in normal operation to a temperature such that if the desired temperature of the heated fluid is exceeded by any substantial amount for a material length of time the heating elements are badly damaged, if not entirely destroyed, through over-heating.

The conditions during starting up and shutting down periods are particularly severe, especially in the case of steam superheaters, as during these periods intense heat may be generated in the furnace when there is insufficient steam flow through the heating elements to properly carry away the heat which they absorb. Assuming the equipment to be properly designed, the life thereof depends largely upon the proper operation of the apparatus, and in case of failure of any part of it, due to over-heating, the first question which arises is whether such failure has been caused by defective design or material, or by improper operation which has permitted the temperature of the heated fluid to rise materially beyond the temperature for which the apparatus was designed.

The principal object of the present invention is the provision of simple and inexpensive means by which it can be readily determined whether or not a certain predetermined maximum temperature of the heated fluid has been exceeded for a period long enough to damage the heating elements. A further object of the invention is the pro-

vision of means of this character accomplishing its function through the medium of a fusible indicator or indicators, and a still further object of the invention is the provision of a fusible indicator of this character which is located out of contact with the heated fluid so that the heat transmitted to the indicator passes from the heated fluid thereto by conduction through a wall of the heating apparatus. The further and more detailed objects of the invention will become apparent from a consideration of the ensuing description of a preferred form of the invention which has for illustrative purposes been shown as applied to a steam superheater.

In the accompanying drawings, forming a part hereof, Fig. 1 is a fragmentary vertical section of a superheater boiler to which the invention has been applied; Fig. 2 is a broken elevation, on an enlarged scale, of the superheater headers and connections, as viewed from the left of Fig. 1; Fig. 3 is a fragmentary section on an enlarged scale taken along the line 3—3 of Fig. 2, and Figs. 4 and 5 are plan and elevation views respectively of the fusible elements employed.

Referring now to Fig. 1, the boiler illustrated is of the semi-vertical or Stirling type, comprising a plurality of steam and water drums 1, 2 and 3, said drums being connected respectively by the banks of generating tubes 4, 5 and 6 to the usual mud drum (not shown). The upper drums are further connected by means of the usual steam and water circulators 7 and 8, and the steam generated in the boiler is taken off through the pipe 9 to the saturated steam header 10 of the superheater, which is of known form and comprises header 10, a similar header 11 for the superheated steam and a plurality of tubular superheating elements 12 connecting the two headers and located in the inter-tube space of the first bank of boiler tubes 4. Steam from the superheater header is carried to the point of use through pipe 13.

As shown more clearly in Figs. 2 and 3, a recess 14 is formed in the wall of the superheated steam header 11 adjacent to its outlet end, this recess preferably being in the

form of a threaded bore extending inwardly from the exterior of the header to a point about a quarter of an inch from the inner surface of the header wall. The amount of 5 metal left between the bottom of the recess and the inner surface of the header wall will obviously differ depending upon the conditions for which the header is designed.

A minimum thickness of metal at this 10 point sufficient to withstand safely the pressures imposed on the header is obviously required, and the maximum thickness is limited by the factor of heat conduction through the metal from the interior of the 15 header.

In the embodiment shown, the fusible elements 15 and 16 comprise two semi-cylindrical stepped plugs having relatively large 20 bases resting on the bottom of the recess and held in position by the plug 17 screwed into the threaded wall of the recess 14.

The fusible elements 15 and 16 may be of any suitable material which will fuse at the 25 desired temperature which it is desired to indicate. In the present instance, as applied to a superheater working in the usual range of temperatures now employed, it is desirable to detect superheat temperatures much in excess of 800° and the element 15 is therefore 30 made of an alloy whose fusing point is in the neighborhood of 850° F. Such an alloy may comprise a mixture of 35.4% lead, 35.4% zinc and 29.2% antimony. In addition to an element indicating this temperature, it is also desirable, in many instances, 35 to provide means for indicating whether or not the normal temperature has been very greatly exceeded, and for this purpose the element 16 is provided having a fusing temperature of approximately 950° F. This element may be made of a mixture of 19.12% lead, 19.12% zinc and 61.75% antimony.

Obviously, the fusible element or elements 40 may be of any material or composition which will fuse at the temperature or temperatures it is desired to record.

In order to prevent or to make known any 45 unauthorized tampering with the fusible elements the plug 17 may be spot-welded as at 18 to form a seal which must be broken before the fusible elements can be reached for inspection or replacement.

The functioning of the device will be largely 50 evident from the foregoing description of the 55 illustrative embodiment shown, as any over-heating of the header will be immediately reflected in the fusing of one or both of the fusible elements located therein. In this connection it is important to note that the 60 location of the header in which the fusible elements are placed with respect to the combustion gases, or other heating medium, is 65 immaterial. The heating medium is in substantially all cases at a temperature sufficient 70 to fuse the fusible elements and the de-

termining factor in their condition and also the condition of the heating elements is the 75 cooling effect of the medium being heated. It is the quantity and temperature of the medium passing through the heating apparatus which determines the temperature of the latter, and consequently of the fusible elements, so that the action of the fusing elements will be the same whether they be placed 80 in a header located in the path of the heating medium or outside such path.

It is furthermore to be noted that with the 85 fusible elements employed in accordance with the present invention a momentary fluctuation in furnace conditions or in the condition 90 of flow or temperature of the fluid being heated will not affect the fusible elements, inasmuch as they are affected only by heat conducted through the wall of the header, 95 which will reach a temperature sufficient to fuse the elements only after abnormal conditions have obtained for a length of time sufficient to cause probable damage to the apparatus. In the specific form of superheater chosen for illustrative purposes, the preferred 100 location for the fusible elements is adjacent to the exit end of the superheated steam header, but this exact location need not necessarily be employed, particularly in other specific forms of apparatus to which the invention 105 may be applied, as the principal requirement is simply that the fusible elements be exposed to the heating effect of the heated fluid at some point in the path of flow which 110 will give an accurate indication of the final temperature of substantially the entire body of heated fluid leaving the heating apparatus.

It is to be understood that the form of apparatus hereinbefore described is illustrative only and that the invention is to be considered as embracing all such changes and modifications as may fall within the terms of the appended claims.

I claim:

1. The combination, with heat exchange 110 apparatus of the surface type having a conduit conveying fluid heated in said apparatus, of temperature indicating means comprising a plurality of fusible elements out of contact with the heated fluid passing through 115 said apparatus and receiving heat from said fluid by conduction through a portion of the wall of said conduits, each of said elements fusing at a different temperature.

2. The combination, with heat exchange 120 apparatus comprising a plurality of heating elements and a header into which they discharge a heated fluid, of temperature indicating means comprising a plurality of elements 125 each adapted to fuse at a different predetermined temperature, said elements being located in juxtaposition and in thermal contact with a portion of the wall of said header, and out of contact with the heated fluid therein.

3. In heat exchange apparatus, a conduit for conveying fluid heated in said apparatus, a recess extending inwardly from the exterior of the wall of said conduit to a point adjacent to the inner surface of said wall, a plurality of elements each adapted to fuse at a different temperature and disposed within said recess, and means for holding said elements in thermal contact with a portion of the surface defining said recess.

4. In heat exchange apparatus, a conduit for conveying fluid heated in said apparatus, a recess extending inwardly from the exterior of the wall of said conduit and having a plane bottom adjacent to the inner surface of the wall, a pair of elements each adapted to fuse at a different temperature and each having a plane surface contacting with a portion of said bottom, and means for holding said elements in position.

5. In heat exchange apparatus, a conduit for conveying fluid heated in said apparatus, a threaded cylindrical recess extending inwardly from the exterior of the wall of said conduit and having a plane bottom adjacent to the inner surface of the wall, an element adapted to fuse at a predetermined temperature, said element having a plane surface contacting with said bottom, and a plug screwed into said recess over said fusible element to hold the latter in position.

6. In heat exchange apparatus, a conduit for conveying fluid heated in said apparatus, a threaded cylindrical recess extending inwardly from the exterior of the wall of said conduit and having a plane bottom adjacent to the inner surface of the wall, an element adapted to fuse at a predetermined temperature, said element having a plane surface contacting with said bottom, a plug screwed into said recess over said fusible element to hold the latter in position, and means for detecting tampering with said plug comprising a seal arranged to be broken by movement of the plug.

7. The combination with heat exchange apparatus having a conduit for conveying heated fluid, said conduit having a recess extending inwardly from the exterior wall thereof, of an element adapted to fuse at a predetermined temperature and having a base contacting with the bottom of said recess, and a closure for said recess over said fusible element holding the latter against the bottom of the recess.

8. In heat exchange apparatus, a conduit for conveying fluid heated in said apparatus, a recess extending inwardly from the exterior of the wall of said conduit and having a bottom adjacent to the inner surface of the wall, a pair of elements each adapted to fuse at a different temperature and each having a base contacting with a portion of said bottom and means for holding said elements in position.

9. In heat exchange apparatus, a conduit for conveying fluid heated in said apparatus, a threaded cylindrical recess extending inwardly from the exterior of the wall of said conduit and having a bottom adjacent to the inner surface of the wall, an element adapted to fuse at a predetermined temperature, said element having a base contacting with said bottom, a plug screwed into said recess over said fusible element and holding the latter in position, and means for detecting tampering with said plug comprising a seal arranged to be broken by a movement of the plug.
